UNITED STATES PATENT OFFICE.

ANTHONY ASTER, OF ROCHESTER, NEW YORK.

AIRPLANE.

1,290,481.

Specification of Letters Patent. Patented Jan. 7, 1919.

Application filed March 1, 1918. Serial No. 219,838.

To all whom it may concern:

Be it known that I, ANTHONY ASTER, a citizen of the United States, residing at Rochester, in the county of Monroe and 5 State of New York, have invented new and useful Improvements in Airplanes, of which the following is a specification.

This invention relates to airplanes and the construction hereinafter described is particularly 10 designed for use in the building and controlling of large flying machines adapted for transport purposes and for covering long distances. One of the principal objects of the present invention is to arrange the supporting 15 planes in such manner that an increased number of planes may be employed in one machine thereby giving the required lifting power for a machine of large size, which must necessarily be equipped with a 20 plurality of engines and propellers.

A further object of the invention is to provide a boat body or nacelle of streamline formation capable of carrying a large number of passengers or freight and capable of 25 rising in flight from land or water and landing either upon the ground or water.

One of the principal objects of the present invention is to provide novel fore and aft balancing means, the same means being 30 utilized for increasing the angle of incidence of both the fore and aft groups of planes to enable the velocity of the machine to be controlled for the purpose of effecting safe landings.

Another object of the invention is to provide means for independently varying the angle of incidence of the fore and aft groups of supporting planes in order that the fore and aft stability of the machine may be controlled by the operator.

With the above and other objects in view, the invention consists in the novel construction, combination and arrangement of parts, herein fully described, illustrated and 45 claimed.

In the accompanying drawings:—

Figure 1 is a side elevation of the improved airplane.

Fig. 2 is a plan view of the same.

Fig. 3 is a front elevation thereof.

Fig. 4 is a fragmentary side elevation on an enlarged scale, showing the means for in-

dependently controlling the fore and aft sets of supporting planes.

Fig. 5 is a fragmentary vertical section on 55 an enlarged scale showing a portion of the controlling means for varying the angle of incidence of the fore and aft groups of planes.

In carrying out this invention, I employ 60 a long narrow boat body or nacelle of streamline formation, the same being provided at a suitable point in the bottom thereof with an angle or step 2 to facilitate rising from the water, the rear portion of the body in 65 rear of the step 2 slanting upwardly as indicated at 3. The deck 4 of the body 1 is formed with a number of port holes 5 which will be glazed and which will form observation openings or windows as well as entrances and exits. By locating the port holes 5 in the deck 4, the interior of the hull will be brilliantly illuminated. The boat body 1 will be of such dimensions that it may contain a large number of passengers 70 or a considerable quantity of freight. Supporting wheels 6 will be mounted under the boat body 1 to enable a landing to be made upon the ground and also to enable the machine to rise in flight from the ground. 80

Located above the boat body 1 and in spaced relation thereto is a fuselage or upper body 7 in the forward portion of which is housed an engine 8 having its shaft 9 extending forwardly through the nose of the 85 fuselage, said shaft having a tractor screw or propeller 10 secured thereon. The fuselage 7 which, like the body 1, is of streamline formation, also contains one or more fuel tanks 11 which are thus housed within 90 the fuselage.

A forward group of planes 12 are connected to the body 1 and the nacelle 7, three of such planes being shown, and in rear of the planes 12 an aft or rear group of planes 95 13 is arranged. In the preferred embodiment of this part of the invention, I employ three or more planes 12 in the forward group and two or more planes in the aft group, there being one plane less in the rear group 100 than in the forward group. This is done in order to prevent interference of the air currents acting on the front planes and the rear planes. In other words the rear planes are

in staggered or alternate arrangement with respect to the forward planes. In addition to this, the rear planes, in a large machine, are located at such a distance from the front planes that the air after acting on the front planes has sufficient time to readjust itself before acting on the rear planes, in order to have the necessary lifting effect on such rear planes.

10 The front planes are connected by struts or posts 14, the planes 12 being connected pivotally at the points 15 with said struts and having an overhang in front thereof. In rear of the struts 14, the trailing portions 15 of the planes are connected by vertical rods 16 of special construction as will hereinafter appear. The rear planes 13 are in like manner pivotally connected at 17 to their posts or struts 18 and the rear portions or edges 20 of the planes are connected by a vertical rod 19 of special formation. As shown in Figs. 4 and 5 the rod 16 is threaded as shown at 20 and is engaged by a nut 21 threaded thereon and capable of being turned by means of 25 a hand wheel 22 which is connected to the nut 21 by means of spokes 23. The nut 21 is held against vertical movement by means of an annular keeper 24 secured to a bar 25 of the machine frame. It will now be observed that by turning the wheel 22 and the nut 21, the rod 16 may be moved upwardly or downwardly thereby correspondingly elevating or depressing the trailing edges of the front planes 12 and changing the angle 30 of incidence thereof. In like manner the shaft 19 is threaded and is engaged by a nut 26 formed integrally with a sprocket wheel 27. Running around the sprocket wheel 27 is a sprocket chain 28 which extends forwardly and passes around a sprocket wheel 29 on a sleeve 30 having fastened thereto a hand wheel 31 by turning which, the nut 26 may be turned for raising and lowering the threaded rod 19. This has the effect of correspondingly elevating and depressing the 35 leading edges of the rear planes 13. The shaft 16 is slideable freely through the sleeve 30 so that the adjustment of the angle of incidence of the front planes may be effected independently of the adjustment of the angle of incidence of the rear planes. This provides for controlling the fore and aft stability of the machine. In making a landing, the speed of the machine may be materially reduced to the point of safety by increasing the angle of incidence by both the front and rear groups of planes.

In addition to the front engine 8 and its propeller 10, I provide two engines 32 which are arranged in rear of the front planes 12 and supported by a suitable frame or brackets 33 at opposite sides of the fuselage 7 and equi-distantly therefrom. Each of the engines 32 has its shaft 34 extending in a forward direction and a propeller 35 mounted

thereon just in rear of the trailing edges of the planes 12. It is proposed to provide suitable means whereby all three of the engines or two or only one thereof may be operated at a time.

At the rear end of the fuselage 7, I mount a vertical rudder 36 having a cross head or arms 37 extending at right angles thereto. Operating connections or cables 38 are secured at their rear ends to the opposite extremities of the cross bar 37 and stays 39 are extended from said cross bar to the trailing edge of the vertical rudder 37. The connections 38 extend forwardly and are attached to the opposite ends of a lever 40. The lever 40 is mounted on a vertical shaft 41 which extends downwardly into the nacelle 7 and it has fast thereon a steering bar 42 under the control of the aviator. The nacelle 7 and the boat body 1 are connected by upright struts or posts 43 between which are inserted crossed stay wires or connections 44 similar to the ordinary king trussing now used in aeroplane construction. One or more of the forward planes 12 will be provided with ailerons or lateral balancing planes 43' in connection with suitable controlling means convenient to the operator. Lateral balancing floats or pontoons 44' will be placed under the bottom plane 12 in order to provide for the proper balancing of the machine while resting on the surface of the water or proceeding at a speed less than the planing speed.

From the foregoing description taken in connection with the accompanying drawings, it will now be seen that I have provided an airplane structure which is especially adapted for large machines intended to carry considerable weight either in passengers or freight. The operator and all other occupants or passengers are housed within a streamline body having a hydroplane surface which will enable it to rise from the water and to land thereon. The construction also provides for reducing the head resistance of the complete structure, enabling the machine to be propelled at great velocity. Additional engines and propellers may be mounted on the machine if occasion demands and additional supporting planes may be provided in accordance with the weight of the machine and the size thereof.

I claim:

1. In an airplane, the combination of a boat body of streamline formation, a fuselage of streamline formation located above and in spaced relation to said boat body, front and rear groups of supporting planes, posts securing said planes to the boat body and fuselage and having said planes pivotally connected thereto between the leading and trailing edges of the planes, a substantially vertical rod connecting the planes of each group at one side of the posts thereof,

- each of said rods being threaded, and manually controlled means embodying nuts having a threaded engagement with said rods for moving said rods upwardly and downwardly to change the angle of incidence. 5 controlled means on said first named rod for operating said nut, whereby the angle of incidence of the front and rear groups of planes may be varied independently of each other.
2. In an airplane, the combination of a boat body of streamline formation, a fuselage of streamline formation located above and in spaced relation to the boat body, 10 front and rear groups of supporting planes pivotally mounted in relation to the boat body and fuselage, a threaded rod connected with the trailing edges of the planes of the front group, a threaded rod connected with the trailing edges of the planes of the group 15 in rear of the front planes, hand controlled means on the first named rod for moving the latter upwardly and downwardly to change the angle of incidence of the planes of the front group, a nut threaded on the second rod for moving the latter upwardly and 20 downwardly to change the angle of incidence of the planes of the second group, and hand
3. In an airplane, the combination of a boat body of streamline formation, a superimposed fuselage of streamline formation in spaced relation to said boat body, means rigidly connecting said body and fuselage, front and rear groups of supporting planes connected with said body and fuselage, an engine housed within said fuselage, a tractor propeller driven thereby and arranged in advance of the front group of planes, engines arranged in rear of the front group of planes and at opposite sides of and equidistantly from the fuselage, and propellers driven by the last named engines and arranged behind the trailing edges of the planes of the front group. 30 35 40

In testimony whereof I affix my signature. 45
ANTHONY ASTER.
